UNITED STATES PATENT OFFICE.

CHARLES LAUNER, OF FITZGERALD, GEORGIA.

CLOTHES-RACK.

SPECIFICATION forming part of Letters Patent No. 674,779, dated May 21, 1901.

Application filed March 17, 1900. Serial No. 9,132. (No model.)

To all whom it may concern:

Be it known that I, CHARLES LAUNER, residing at Fitzgerald, in the county of Irwin and State of Georgia, have invented certain new 5 and useful Improvements in Clothes-Racks, of which the following is a specification.

The object is to present a clothes-rack in which the rack-frame may be adjusted and held at any desired height, thus to facilitate 10 the placing thereon or the removal therefrom of articles to be dried or aired.

The invention consists in the novel construction and combination of parts of a clothes-rack, as will be hereinafter fully described and claimed.

In the accompanying drawings, forming a part of this specification, and in which like letters of reference indicate corresponding parts, Figure 1 is a view in side elevation of 20 the upper portion of the rack. Fig. 2 is a view in top plan.

Referring to the drawings, A designates a post or upright, preferably circular in cross-section, which may be either sunk in the 25 ground or be secured to a floor, roof, or other support. Upon the post are placed two four-armed runners B, the same being held at the requisite distance apart by spacing-blocks b. To the lower portion of the spacing-blocks are 30 secured the rack-arms C, which may be of any desired length and are inclined upward from the post, so that the clothes-lines c will be properly spaced apart to facilitate the hanging of garments thereon. These lines c may 35 be secured to the arms C in any preferred manner, as by pins or hooks c², around which the lines may be passed, as shown in Fig. 1. The arms C are held from sagging by braces c³, the ends of which are secured, respectively, 40 to the upper portion of the spacing-blocks and to the rack-arms near their outer ends, as clearly shown in Fig. 1. Upon the top of the post is mounted a pulley-support D, comprising a base d, held on the post for pivotal 45 movement by a spike d², and two braces d³, supporting a grooved sheave or pulley d¹. The groove of the sheave is engaged by a cord d⁵, preferably of metal, and one end of this cord d⁵ is secured in any suitable manner to

the "rack-frame," by which name I designate 50 the entire clothes-supporting portion of the apparatus, and the other end carries a pulley-block d⁶, the pulley of which is engaged by a rope or cord d⁷, having one end secured in any suitable manner to the rack-frame, 55 the free portion to be brought into engagement with a cleat c⁴, carried by one of the arms C, to hold the rack-frame at any desired adjustment as to height.

The manner of using the device will be obvious. The rack-frame is first lowered to bring it within easy reach, and the clothes or other articles are strung on the lines c. The rope d⁷ is then drawn down until the rack-frame is raised as high as may be desired and 65 is held thus raised by securing the rope around the cleat c⁴.

By mounting the base d for pivotal movement on the post A twining of the cords d⁵ and d⁷ around the post when the rack-frame 70 is revolved is obviated.

Having thus fully described my invention, what I claim as new, and desire to secure by Letters Patent, is--

A clothes-rack comprising, in an organized 75 structure, a support, four-armed runners mounted thereon, spacing-blocks secured to the arms of the runners for holding the latter at the proper distance apart, rack-arms secured to the lower portion of the spacing-blocks, braces connected with the upper portion of the spacing-blocks and with the arms near their outer extremities, hooks carried by the said arms, lines held on the arms by the hooks, a sheave supported for pivotal 85 movement on the upper end of the support, a rope or cord secured at one end to the rack-frame and passing over the sheave, a pulley-block carried by the free end of the rope or cord, a cleat carried by the said frame, and 90 a rope secured at one end to the said frame and passing through the pulley-block, the free end of the latter rope to engage the said cleat, substantially as described.

CHARLES LAUNER.
